ANTISEPTIC APPLYING APPARATUS.

(Application filed June 4, 1898.)

(No Model.)

3 Sheets—Sheet 3.

A technical line drawing of a wheel assembly, labeled 'Fig. 5'. The assembly features a central hub with a flange (68) and a hub cap (69). Spokes (70) extend from the hub to the rim. A side-mounted mechanism is shown, including a coil spring (64), a lever (66), a valve (67), and a rod (68). The assembly is mounted on a frame (71) with a wheel (72). The drawing is signed 'S.H.' in the bottom right corner.

UNITED STATES PATENT OFFICE.

WILBER M. KELSO, OF CHICAGO, ILLINOIS.

ANTISEPTIC-APPLYING APPARATUS.

SPECIFICATION forming part of Letters Patent No. 679,262, dated July 23, 1901.

Application filed June 4, 1898. Serial No. 682,588. (No model.)

To all whom it may concern:

Be it known that I, WILBER M. KELSO, a citizen of the United States of America, and a resident of Chicago, county of Cook, and 5 State of Illinois, have invented certain new and useful Improvements in Antiseptic-Applying Apparatus, of which the following is a specification.

My invention relates to apparatus for sprinkling, spraying, or atomizing an antiseptic solution.

The prominent objects of my invention are to provide for the effective and efficient spraying or sprinkling of the ground or the floors, 15 walls, or ceilings of buildings or cars or the like; to provide wheeled apparatus respectively adapted to apply the antiseptic solution to streets, the ground, and to the interior of buildings, cars, and the like objects 20 or articles; to arrange for the continuous and steady application of the antiseptic in the way mentioned; to allow the easy and rapid handling of the devices employed for the purpose and their manipulation and transportation for the progressive application of 25 the antiseptic; to provide practical, inexpensive, and easily-constructed devices for such purposes, and to accomplish the aforesaid results in an efficient manner.

To the attainment of the foregoing and other desirable ends my invention consists in matters hereinafter set forth.

In the accompanying drawings, Figure 1 is a side elevation of an antiseptic device embodying my invention and particularly adapted for spraying or sprinkling streets or the ground with an antiseptic solution and having portions broken away for convenience of illustration. Fig. 2 is a rear elevation. Fig. 40 3 is a plan view of the same, also having portions broken away for convenience of illustration. Figs. 4, 5, and 6 are views, partly in vertical section and partly in elevation, of details of the apparatus, all taken on a larger 45 scale. Figs. 7 and 8 are respectively elevation and plan views of an apparatus particularly adapted for spraying the interior of buildings, cars, and the like.

In Figs. 1 to 6, inclusive, of the drawings 50 I have shown a wheeled apparatus for sprinkling, spraying, or otherwise applying an an-

tiseptic solution to streets or roads as the vehicle passes over them.

In Figs. 7 and 8 I have shown a wheeled apparatus adapted to be propelled by hand-power for similarly applying an antiseptic solution to the floors, walls, and interior generally of buildings, railroad-cars, and the like.

The apparatus for street use involves a suitable vehicle mounted on the rear and front 60 pairs of wheels 30 and 31, respectively, which wheels are in turn mounted on the rear and front axles 28 and 29, respectively. The front axle 29 is arranged so that it can be deflected to either side, so as to permit the vehicle to 65 be properly turned. The body-frame of the vehicle involves a couple of horizontally-arranged side bars 32 32, supported by springs 44 44, which extend longitudinally above the rear axle 28, thence upwardly at a point between the two axles, so as to provide space which the front wheels can occupy when they are in a turned position. These bars 32 curve thence downwardly and are formed into the rear and the lower portion of a box 33, which 70 is positioned and supported by springs 34 above the front axle 29. On top of this box 33 is arranged a suitable seat 35 for the operator of the vehicle. In front of this seat is arranged a lever 36, by means of which the 75 front wheels can be suitably turned. The vehicle is desirably constructed so that it can be propelled over the ground either by horse-power or by the power of a motor carried by it. To such end the front axle is constructed so that a pole can be attached to it. As an arrangement for driving the vehicle by a motor on board of it I have shown an electric motor 37, arranged below the rear axle 28 and having its armature mounted upon a 80 rotary shaft 38. The motor 37 is conveniently suspended below the axle 28 by means of a couple of pairs of supporting-braces 41, having their upper ends secured to the horizontal rods 42 42. These rods 42 42 are held 85 in position against forward and backward swinging movement by guides 43, extending upward from their upper ends through the side bars 32 32. The shaft 38 is connected 90 so as to permit of its driving the rear wheels 30 30 by a couple of pairs of gear-wheels 39 39 and 40 40, respectively, on its opposite

ends and on the opposite ends of the rear axle 28. The particular construction employed for connecting the gear-wheels 40 with the rear wheels of the vehicle 30 will be described hereinafter.

The solution which is to be applied to roads, streets, or the like is contained in the rear portion 1 of a suitably-sized horizontally-arranged divided tank or reservoir A. From 10 this rear water or solution compartment of the reservoir A it is forced into and through the interior tube 2 of a double hose B and thence out of the inner spout 3 of the nozzle C, attached to said hose B, as best shown in 15 Fig. 5. In this way the antiseptic can be readily applied to the ground or street as the vehicle progresses. It is frequently desirable, however, to supply or force air into the solution as it leaves the dispensing-nozzle in 20 order to form it into a light mist or very fine spray. To such end I have shown means and arrangement by which air can be forced into the antiseptic solution as the latter leaves the nozzle. This arrangement involves a compartment 25 10 of compressed air conveniently formed at the forward end of the tank or reservoir A and an outer tube 11 of the hose B, through which outer tube 11 air is forced from the air-compartment 10 to and through the 30 outer shell 12 of the nozzle C. In this way the antiseptic solution and the air are simultaneously forced through the same hose into the same nozzle and mingled at the outlet of that nozzle in a way to produce a fine spray 35 or mist.

In order to permit the formation of spray having relatively different amounts of antiseptic solution and air under pressure in it, I construct the nozzle C in such a way that 40 the amounts of these elements leaving it can be either independently or jointly regulated. The amount of antiseptic solution discharged is regulated by turning the inner shell 3 of the nozzle C by means of a flange 13, formed at 45 its end about its screw-threaded connection with the metal hose-terminal 15, so as to draw the aperture at its outer end into greater or less proximity to the outer end of the plug 14, which is arranged centrally within it and 50 which is rigidly connected to or made integral with the end of the metal hose-terminal 15. In this way the opening of the aperture at the forward end of the nozzle-shell 3 is varied in size, so as to vary the discharge of the antiseptic solution. The discharge of air under pressure is regulated by turning the outer shell 12 of the nozzle C about its screw-threaded connection with the inner shell 3 thereof by means 55 of a flange 16 at its inner end. In this way 60 the distance of the outer shell from the inner shell 3 is varied, so as to vary the space between the two, and thereby vary the discharge-opening formed between their walls.

In order to permit the free and unrestrained 65 adjustment of the inner shell 3 by means of its flange 13, the outer tube 11 of the hose B is terminated at a point to the rear of the

connection of such shell with the terminal 15 and is connected with the outer shell 12 of the nozzle C by means of a supplementary 70 hose 17. In this way access is readily obtained to the flange 13 or other adjusting medium on the inner shell 3. While the hose 17 could be connected with the outer nozzle-shell 12 in any suitable way, it is shown as 75 connected therewith so as to permit an extent of rotation thereof sufficient to produce the desired variation in the air-discharge opening.

For convenience of manipulation and storage the hose B is arranged for coiling upon a reel D, which is conveniently positioned above the forward end of the tank or reservoir A.

As an arrangement for connecting the two tubes of the hose B to the water or solution and air compartments of the reservoir A and at the same time for securing the end of the hose B to the reel D, so that the hose can be used with any portion of its length coiled upon the reel and also so that it cannot be withdrawn and separated from the latter the inner end of the tube 2 is attached to the outer end of a pipe 6, which extends radially outward from the interior of the reel and has its outer end terminated substantially flush 95 with the cylindrical shell of the reel, and the outer tube 11 is attached to a second radially-arranged pipe 18, which incloses the pipe 6. These radially-arranged pipes 6 and 18 form branches or continuations of a pipe 7, 100 which latter extends through and forms the axis with and upon which the reel rotates. The end portions of the pipe 7, however, are not in communication with one another, and the left-hand end portion (referring to Fig. 105 4) communicates with the inner pipe 6, while the right-hand end portion communicates with the outer radial pipe 18. In this way the antiseptic solution and the air under pressure are readily conveyed to the inner and outer tubes of the hose B, and as a result the left-hand portion, or the portion 7^a of the pipe 7, becomes a water or solution pipe and the right-hand portion, or the portion 7^b, becomes an air-pipe. The end portion 7^a of this rotating and reel-supporting pipe 7 is connected with a water or solution pipe 8, which forms substantially a continuation of it and which extends outwardly from the pipe 7 and thence downwardly and into the 110 water-compartment of the tank or reservoir A, as best shown in Fig. 2. The air end 7^b of the pipe 7 is similarly connected to a valved air-pipe 19, which likewise extends outwardly and thence downwardly and is connected to 115 the reservoir or tank A, so as to communicate with the air-compartment 10 thereof, as best shown in Fig. 1.

In order to permit the rotation of the reel-supporting pipe 7, it is connected with the 120 pipes 8 and 19 by rotary or universal joints 99.

The solution and the air in their respective compartments could be subjected to pressure or otherwise forced out of the same by any

suitable arrangement or apparatus. As a very simple and efficient arrangement for such purpose, however, I have shown an air-pump 20, Fig. 1, and have connected it by suitable connections, so as to force air at will either into both the solution and air compartments or into the solution-compartment alone. In the arrangement I have shown the air is forced from the pump and flexible connection or 10 hose 21, from which latter it passes into a pipe 22. This pipe is arranged horizontally below the tank or reservoir A and has its forward end connected therewith, so as to communicate with the air-compartment 10 thereof, and has its rear end connected with a pipe 23, which extends upwardly within the solution-compartment substantially to the top thereof. In this way air can be supplied to both the solution and air compartments of 15 the tank or reservoir A. When it is desired that both these compartments shall receive air under pressure, both of the valves 24 and 25 in the horizontally-arranged pipe 22 are opened, and when it is desired that but one 20 of such compartments only shall receive air under pressure the proper valve 24 or 25 is opened.

The degree of pressure in the air and water compartments of the reservoir A can be 30 indicated by pressure-gages 45 and 46, which are positioned in front of the driver's seat 35 and are connected, respectively, with the air and water or solution compartments by suitably-valved pipes 47 48, extending between 35 the gages and the tank or reservoir A, as best shown in Figs. 1 and 3.

The pump 20 can be of any suitable construction and can be operated in any desired manner. As a preferred arrangement it consists in a cylindrical plunger-pump and is arranged and connected in such a way that it can be operated either by the motor 37, which drives the vehicle, or by the rear wheels thereof when the vehicle is not driven by a 45 motor, but is drawn by horses. In such arrangement the pump is disposed horizontally near the forward end of the tank or reservoir A and is operated by a reciprocating piston-rod 26, which is in turn driven by an eccentric 27 on the rear axle 28 of the vehicle. The eccentric 27 is desirably arranged and connected so that it can be operated either by the electric motor which drives the vehicle either when the vehicle is stationary or moving 50 or by the rear wheel or wheels 30 when the vehicle is moving. The arrangement which I have shown for accomplishing this end, and also for allowing connection to be made and severed between the motor and the 55 rear wheels for driving the vehicle, and also for permitting it to be drawn without causing the rotation of the motor or the operation of the pump is particularly illustrated in Figs. 3 and 6 of the drawings. In this construction the rear wheel 30 is loose upon its axle 28 and is desirably provided with ball-bearings, so as to decrease friction in its rotation. The

portion of the axle 28 between the wheel 30 and the downwardly-extending portion of the former is surrounded by a sleeve 50, which 70 is free to rotate about the axle 28 independent of the wheel 30. This sleeve forms the axle for the motor gear-wheel 40 and also for the eccentric 27, both of which are loosely mounted upon it, so as to permit their rotation independently of the sleeve and also independently of one another. Upon one end of the sleeve is mounted a clutch 51, which is keyed to the sleeve 50, so as to permit it to slide thereupon, and which can engage the 80 motor-gear 40, so as to cause the rotation of the latter with the sleeve 51. At the outer end of the sleeve 50 are a couple of clutches 52 and 53, both of which are likewise keyed to the sleeve 50, so as to permit their sliding 85 movement thereupon, and the former of which is adapted to engage the eccentric 27 and the latter to engage the wheel 30. When it is desired to drive the wheel 30 without driving the pump, the inner clutch 51 is slid into engagement with the wheel 40, so as to cause the sleeve 50 to be rotated by the latter, and the outer clutch 53 is slid outwardly into engagement with the wheel 30. In this way motion is communicated from the motor-gear 40 95 to the sleeve 50 and thence to the wheel 30. If it is desired at such time to drive the pump as well, the intermediate clutch 52 is slid inwardly into engagement with the eccentric 27, so that in this way the eccentric 27 is 100 also rotated in conjunction with the driving-sleeve 50.

If it is desired to operate the pump by the vehicle-wheel instead of by the motor, the motor-connecting clutch 51 is moved out of 105 engagement with the wheel 40, the clutch 53 is moved into engagement with the wheel 30, and the intermediate or pump-connecting clutch 52 is moved into engagement with the eccentric 27. In this way power is communicated from the wheel 30 to the driving-sleeve 110 50 and thence to the eccentric 27, while at the same time the motor-gear 40 and the motor-connecting clutch 51 remained stationary.

If it is desired to operate the pump while 115 the vehicle is stationary, the motor-clutch 51 is moved into engagement with the motor-wheel 40, the pump-connecting clutch 52 is moved into engagement with the eccentric 27, and the wheel-connecting clutch 53 is 120 moved out of engagement with the wheel 30. In this way power is transmitted from the motor to the gear-wheel 40, thence to the sleeve 50, and thence to the eccentric 27, while the wheel 30, and therefore the vehicle, 125 remains stationary. It will be observed that this is an exceedingly simple, inexpensive, and practical arrangement for the accomplishment of the various results enumerated. These various clutches 51, 52, and 53 are 130 respectively operated by a series of levers 54, 55, and 56, which are connected with their allotted clutches by suitable straps arranged over the latter and which extend rearwardly and are

pivotedly connected to the pump-supporting frame-bar 58.

It will be observed that in the drawings but one side of the machine is shown, the right-hand wheels being attached in Fig. 1 and the left-hand rear wheel being attached in Fig. 2 and but one side of the machine being shown in Fig. 3. The operating mechanism above described for operating the pump and propelling the vehicle is therefore shown on but one side of the apparatus. If desired, the apparatus can be provided with such mechanism on but one side of the machine, as shown in the drawings, or it can be constructed with such mechanism on both of its sides, it being understood that in the latter case the mechanism on the other side corresponds to that shown in the drawings and also that in operating it the levers 54, 55, and 56 are arranged in their proper positions for the various operations in the same way on opposite sides of the apparatus. This last-mentioned arrangement of employing two sets of such pump-operating and vehicle-driving mechanism is the preferred one.

The electric motor 37 can be driven in any desired way. As a preferred arrangement it is driven by a battery of storage-cells E, which as a matter of further improvement are confined in the box 33, supported over the front axle 29. The connections between these storage-cells E and the motor 27 are the usual connections for operating an electric motor and are not shown or described herein, as they are well known and form no part of my present invention.

The manually-operated apparatus illustrated in Figs. 7 and 8 is the same in general arrangement and plan as the power-driven vehicle heretofore described. In this manually-operated vehicle a divided tank A' is arranged between and carried by a couple of large wheels 60. The tank A is divided into water or solution and air compartments 1 and 10, as in the case of the power-driven vehicle. A hose B' is connected with pipes 61 and 62, extending, respectively, into the air and solution compartments, and is conveniently coiled about a handle 64, which is secured to the rear end of the tank or reservoir A'. It will be understood that this hose is double in construction, as shown and described in connection with the power-driven apparatus. The pump 20^a for compressing air into the two compartments 1 and 10 is for convenience arranged upon and secured to the top of the tank or reservoir A'. The compressed air is conveyed from it to the two compartments by suitably-valved pipes 65 and 66, leading from the pump to them. The pump 20^a is operated by a crank formed in a shaft 67, which is arranged transversely above the tank or reservoir A' and is supported in suitable bearings extending upward from the wheel-axle. This shaft 67 is rotated by the wheel-axle through the medium of a couple of sprocket-wheels 68 and 69, re-

spectively, on the shaft 67 and a wheel-axle and a sprocket-chain 70, traveling upon the wheels 68 and 69. This hand-propelled vehicle can be rested when not in use upon a small auxiliary wheel 71, carried at the lower end of the track 72, which latter is secured to the forward portion of the tank or reservoir A'.

It will be observed that my invention affords simple, inexpensive, and practical means for sprinkling, spraying, or otherwise applying an antiseptic solution and also provides novel and efficient devices and combinations for operating the vehicle and the solution-discharging mechanism.

As many of the devices and constructions thereof can be changed without departing from the essence of my invention, I do not wish to limit myself to the specific devices and constructions shown herein, although I consider such devices and constructions particularly well adapted for accomplishing the desired results, and therefore consider them matters of special and further improvement.

What I claim as my invention is—

1. In a wheeled antiseptic apparatus, the combination with a motor and a source of power therefor carried by the vehicle for supplying compressed air; air and solution tanks; connections for supplying air under pressure from the pump to either or both of said tanks at will; spraying devices provided with means for regulating the relative amounts of air and solution emitted; and connections for operating the pump and driving the vehicle by the motor, either alone or together.

2. In an antiseptic-applying apparatus, a discharge-nozzle comprising air and solution outlets and means for adjusting the size of either or both of said outlets.

3. In an antiseptic apparatus, the combination with solution and air tanks, and with suitable devices for discharging the solution and air as desired, of means for supplying air under pressure; and suitable connections between such means and the solution and air tanks for supplying the air under pressure to either or both of the tanks, at will.

4. In a wheeled antiseptic apparatus, the combination of a tank or reservoir having solution and air compartments; a hose having two passages or ducts which are respectively connected with the solution and air compartments, and also having a nozzle which is adapted to permit the simultaneous discharge of both the solution and air; a pump for supplying air under pressure; suitable connections between the pump and the air and solution compartments, for supplying compressed air to either or both of the same at will; an electric motor and a storage battery for operating the same; and mechanism for connecting the electrical motor so as to drive the vehicle and also so as to operate the pump either when the vehicle is in motion or at rest.

5. A wheeled antiseptic device, comprising

a suitable body-frame mounted on front and rear wheels and axles; a horizontally-arranged tank or reservoir having air and solution compartments; a hose consisting of interior and exterior tubes respectively connected with the solution and air compartments; a nozzle attached to the end of the hose and adapted to permit the discharge of the solution and air as desired; a pump adapted to supply air under pressure and connected with both the air and solution compartments; an electric motor suspended below the rear axle; and mechanism for either propelling the vehicle or operating the pump, or both, by means of the electric motor, at will.

6. In a wheeled antiseptic apparatus, the combination with pumping means and means for driving the vehicle, of a rotary driving-sleeve; mechanism for connecting the motor with the driving-sleeve so as to cause the rotation of the latter; mechanism for operating the pumping means; and means for connecting and disconnecting the driving-sleeve with the mechanism for operating the pumping means at will.

7. In a wheeled antiseptic apparatus, the combination with a motor for propelling the vehicle, and with the wheel-carrying axle having its wheel loosely mounted upon it, and also with a reciprocating pump, of a rotary sleeve revolving about the wheel-axle; a gear-wheel driven by the motor and revolving about the driving-sleeve; an eccentric for operating the pump and revolving about the driving-sleeve; a clutch for connecting and disconnecting the driving-sleeve with the eccentric and with the motor gear-wheel, respectively.

8. In an antiseptic apparatus, the combination of a hose having a couple of passages and also having a nozzle adapted to permit dis-

charge from both passages, of a rotary reel upon which the hose can be coiled; a rotary pipe serving as the axle of the reel and having its opposite ends out of communication with one another and respectively connected with the two passages of the hose; and side pipes supporting the reel and connected with the opposite ends of the reel-carrying pipe so as to permit the rotation of the latter.

9. In an antiseptic-applying apparatus, the combination with a hose comprising interior and exterior tubes, and with a nozzle adapted to permit discharge from both tubes, of a rotary reel upon which the hose can be coiled; a rotary reel serving as the axle of the reel and having its opposite ends out of communication with one another; interior and exterior branch pipes extending radially outward from the rotary reel-carrying pipe, and connected respectively with the opposite ends thereof; a couple of side pipes supporting the reel; and swivel or rotary joints connecting such pipes with the opposite ends of the reel-carrying pipes.

10. A discharge-nozzle comprising a head provided with a rigid outwardly-extending plug; an inner shell screw-threaded upon the head and having an aperture which can be varied in size by the plug as a result of screwing the shell upon the head; and an outer shell screw-threaded upon the inner one, and forming between the same and itself a passage-way which can be varied in size by a relative movement between the two shells.

Signed by me at Chicago, Illinois, this 2d day of June, 1898.
